Primary Examiner — Keli L Hill*Assistant Examiner* — Harold E Blackwell, II(74) *Attorney, Agent, or Firm* — Ruggiero, McAllister & McMahon LLC**(57) CLAIM**

The ornamental design for a pole mount, as shown and described.

DESCRIPTION

FIG. 1 is a perspective view of a pole mount according to the present disclosure;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view thereof.

The features shown in broken lines form no part of the claimed design.

1 Claim, 5 Drawing Sheets(56)
